APPARATUS FOR FORMING STRAND ASSEMBLIES

Henry R. Massingham, Westfield, N. J., assignor to Western Electric Company, Incorporated, New York, N. Y., a corporation of New York

Application July 1, 1938, Serial No. 216,898

2 Claims. (Cl. 66—9)

This invention relates to an apparatus for forming a covered strand assembly, and more particularly to an apparatus for forming insulated electrical conductors.

5 In some of the many instances where insulated electrical conductors are employed the conductors are subjected to various treatments or tests, such as twisting and bending, and it is usually important that the bare conductors do not project through the insulation during such treatments.

10 Objects of the invention are to provide a simple, efficient and practical apparatus for forming a strand assembly.

15 With these and other objects in view, the invention comprises an apparatus for forming a strand assembly which comprises a unit for twisting a selected number of strands in one direction, mechanism for knitting a cover on 20 the strands in one direction, and a similar mechanism for knitting a second cover thereon in the opposite direction.

25 Other objects and advantages will be apparent from the following detailed description taken in conjunction with the accompanying drawing, wherein

Fig. 1 is a fragmentary side elevational view of the apparatus, and

30 Fig. 2 is a fragmentary view illustrating a strand assembly formed by the apparatus shown in Fig. 1.

In the present embodiment of the invention a selected number of strands 10 is fed to a strand twisting unit 11. Although six strands are shown 35 in the present instance, it should be understood that any desired number of strands may be selected. The strands 10 are guided over a plurality of sheaves 12, rotatably carried by the twisting unit 11, to guide the strands to a twisting point 13 where they are twisted together 40 during their advancement while the unit 11 is rotated through a pulley 14 operatively connected to suitable drive means (not shown). The strands are advanced at a suitable speed by 45 any desired means (not shown) such as a capstan and during advancement the strands pass from the twisting point 13 through a tubular member 16, which is part of the unit 11 and upon which the pulley 14 is mounted. The twisted 50 strands, upon leaving the unit 11, pass over sheaves 18 and 19 and are directed downwardly through a tubular guide 21 of a knitting unit 22. The guide 21 is carried by cross bar 23 supported by uprights 24 (only one of which is shown in 55 the drawing), the latter being mounted upon a

base 25 which also serves as a support for the knitting unit 22. A bracket 26 adjustably secured to one of the uprights 24 has vertically extending pins 27 to rotatably support on the bracket a plurality of tension discs 28. Strands 5 or threads 29 of suitable material such as textile cotton are fed around the tension discs 28 from suitable supply means (not shown). A plurality of thread guides 33 in the form of pins with apertures in the ends thereof through which the 10 threads may pass are adjustably secured in spaced apertures in an annular supporting member 34, the latter being adjustably mounted upon the tubular guide 21.

Another knitting unit 42, having a tubular 15 guide 41 positioned thereabove and supported by a cross bar 43 mounted upon uprights 44, is supported by a base 45 upon which the uprights 44 are also mounted. A bracket 46, having pins 47, 20 rotatably supports sheaves 48 around which 20 strands or threads 49 are directed from suitable supplies (not shown). The threads 49 pass through apertures in the ends of thread guides 53 which are adjustably mounted in apertures of an annular supporting member 54, the latter 25 being adjustably mounted upon tubular guide 41.

The detailed construction of the knitting units is not shown in the drawing nor described in the specification, these units being shown and described in detail in Patent No. 2,126,250, issued August 9, 1938, to Ben K. Ford.

To illustrate the present embodiment of the invention the twisting unit 11 is rotated counter-clockwise, looking from the top, thus twisting the strands together to form a core. The strands 25 thus twisted are advanced to the knitting unit 22 where, at point 56, a knitted cover is formed upon the twisted strands. The knitting units shown are of the type which form interconnected loops on the outside of the needle carrier, the 40 loops while being formed extending in the direction of rotation of the needle carrier, but when pulled over the top of the needle carrier and onto the twisted strands their positions are reversed and they extend spirally in a direction opposite the direction of rotation of the needle carrier. These interconnected loops of successive threads are commonly known as wales. The needle carrier 57 of the knitting unit 22 is, therefore, rotated clockwise, looking from the top, 50 causing the knitted cover to be formed on the strands with the wales thereof extending in the same direction as the twist of the strands. This knitted cover is indicated at 58 in Fig. 2, which figure illustrates the twist in the strands and 55

the wales in the cover 58 as being in the same direction.

The twisted strands with the cover 58 are advanced to the knitting unit 42 where, at point 5 59, a second cover is formed. This second cover is knitted over the first cover but the wales thereof extend in a different direction due to the rotation of the needle carrier 60 of the knitting unit 42 in a direction opposite that in which the 10 needle carrier 57 is rotated. As a result of the last knitting operation the wales of the cover 61 extend transversely with respect to those of the cover 58. However, the courses, which include the float bars of the respective threads, extend 15 longitudinally of the axis of the core consisting of the intertwined strands.

When the finished insulated strand assembly shown in Fig. 2 is twisted in either direction the knitted loops of one cover might tend to loosen 20 but the twist would tighten the knitted loops of the other cover. For example, let it be assumed that the assembly was given a twist in a direction which would tend to loosen the strands. Such a twist would tend to loosen the cover 58 25 but would effect a tightening of the cover 61, thus preventing any of the strands from passing through the covers and becoming exposed. A twist of the strand assembly in the opposite direction would tend to loosen the cover 61 but 30 such a twist would tighten the strands, bringing them closer together, if possible, and at the same time tighten the cover 58 upon the strands. When the strand assembly is bent the portions of the covers adjacent the inner arc of the bend 35 will tend to loosen but the portions adjacent the outer arc thereof will tighten, thus eliminating any possibility of the strands becoming exposed.

It is, therefore, possible for the strand assembly to be subjected to the usual twisting and bending without danger of the conductor strands being exposed through the insulating covers.

It should be understood that the covers may 5 be applied to untwisted strands, that the directions of twist in the strands and the directions of the applications of the knitted covers may be varied, that the covers may be formed with the courses extending spirally in transverse directions about the core and the wales extending longitudinally of the core, and that the embodiment of the invention herein disclosed and illustrated may be otherwise modified and departed from in many ways without departing from the 15 spirit and scope of the invention, as pointed out in and limited only by the appended claims.

What is claimed is:

1. In an apparatus for forming strand assemblies, means to intertwist electrical conductor strands in one direction, and separate means to knit successive covers on the twisted strands with the wales of one cover extending substantially in the same direction as the direction of twist of the strands and transverse to the 25 direction of the wales of another cover.

2. In an apparatus for forming strand assemblies, means to intertwist electrical conductor strands in one direction, means to knit a cover on the twisted strands with the wales of the cover 30 extending substantially in the same direction as the direction of twist of the strand, and means to knit a second cover on the first cover with the wales of the second cover extending in a direction transverse to the direction of the wales of the 35 first cover.

HENRY R. MASSINGHAM.
